UNITED STATES PATENT OFFICE.

RUSSELL C. BURKET, OF POTTSVILLE, PENNSYLVANIA.

ATTACHMENT FOR CONCRETE MIXERS.

Application filed December 16, 1927. Serial No. 240,538.

This invention aims to provide a simple means whereby a measured quantity of liquid of any desired kind, for instance, calcium chloride solution, may be discharged 5 into a cement mixture, when the skip is raised.

It is within the province of the disclosure to improve generally and to enhance the utility of devices of that type to which the 10 invention appertains.

With the above and other objects in view which will appear as the description proceeds, the invention resides in the combination and arrangement of parts and in the 15 details of construction hereinafter described and claimed, it being understood that changes in the precise embodiment of the invention herein disclosed, may be made within the scope of what is claimed, without departing from the spirit of the invention.

In the drawings:

Figure 1 shows in elevation, a cement mixer whereon the device forming the subject matter of this application has been 25 mounted, the skip being lowered;

Figure 2 is a view similar to Figure 1, the skip having been raised;

Figure 3 is an elevation on an enlarged scale, showing the measuring receptacle in 30 the position of Figure 1, parts being in section;

Figure 4 is an elevation showing the measuring receptacle in the position of Figure 2 (approximately), parts being in section;

Figure 5 is a longitudinal section of the 35 mixer for the solution;

Figure 6 is an end elevation of the structure shown in Figure 5;

Figure 7 is a cross section on the line 7—7 40 of Figure 5.

The numeral 1 marks a cement mixer including a container 2 in which the aggregate is mixed, the container, in the present embodiment of the invention, being a rotatable drum. The numeral 3 marks a delivery member or skip which is pivoted at 4 to the frame work of the mixer 1, so that the skip 45 can be swung upwardly or downwardly, the operating means for the skip being of any desired sort. The material to be mixed is placed in the skip whilst the skip is lowered, as shown in Figure 1, and when the skip is raised by the means shown at 5, the material in the skip is discharged into the drum 2, in 50 a way well understood by those skilled in the art.

The numeral 6 marks a measuring receptacle provided at one end with an air outlet, the outlet 7 being prolonged in a direction approximately at right angles to the receptacle 6. The outlet 7 carries a casing 8 in which is mounted a float-actuated check valve 9. The measuring receptacle 6 is secured to the side of the skip in such a position that when the skip 3 is lowered, the longitudinal axis of the receptacle 6 will be disposed in an approximately horizontal position, as indicated in Figure 1 of the drawings.

The numeral 10 designates a supply pipe, 70 which may be flexible, and the numeral 11 marks a discharge pipe which may be rigid. The discharge pipe 11 extends along the side of the skip 3 and is connected thereto by clips 12 or otherwise. The end of the discharge pipe 11 is marked by the numeral 14, and is so disposed upon the skip 3 that when the skip is raised from the position of Figure 1, to the position of Figure 2, the pipe 11 will discharge into the drum 2 of the 80 cement mixer 1.

The numeral 15 marks a valve casing. The pipe 11 is mounted in one end of the casing 15, and the pipe 10 is connected to one side of the casing 15. The valve casing 85 15 has ports 16, 17 and 18. The port 16 communicates with the supply pipe 10. The port 17 communicates with the discharge pipe 11. The port 18 is located at the opposite end of the casing 15 from the port 17 90 and communicates with the outer member 19 of an outlet and inlet tube, the member 19 of the tube being mounted in one end of the casing 15. The inner member of the outlet and inlet tube is designated by the 95 numeral 20 and is connected by means of a coupling 21, to the outer member 19 of the tube. The inner member 20 of the tube is threaded for adjustment into a reinforcing foot plate 22, secured to the end of the 100 measuring receptacle 6. The inner member 20 projects into the measuring receptacle 6, as shown in Figure 4.

A valve 23 is mounted to rock in the valve casing 15. An arm 24 is secured to the outer 105 end of the valve 23 and carries a weight 25. The valve 23 is supplied with ports 26, 27 and 28.

A tank 50 is mounted as indicated at 51 on the frame of the cement mixer 1. In the 110 tank 50 there is a partition 52 forming chambers 53, access being had to the cham-

bers 53 by hinged and latched doors 54 on the tank 50. There is a gland 55 in the partition 52. Bearings 56 are mounted in the ends of the tank 50 and carry glands 57. A shaft 58 is journaled in the glands 55 and 57 and in the bearings 56. The shaft 58 may be rotated by hand, through the instrumentality of a crank 59 on one end of the shaft, or by means of a pulley 67 on the other end 10 of the shaft. Agitators 60, in the form of screws, are located in the chambers 53 the tubular hubs for the agitators 60 carrying set screws 61 whereby the agitators are secured to the shaft 58 to rotate with the 15 shaft. Vertical tubes 62, which are transparent, are mounted on the ends of the tank 50, and are in communication with the tank. Hydrometers 63 are mounted to float in the tubes 62. The tank 50 has outlets 64 communicating with the chambers 53. Valves 65, under the control of an operator, are located in the outlets 64. The outlets 64 are in communication with a pipe 66 which, in its turn, is connected to the supply pipe 10.

25 When either of the doors 54 is opened, the ingredients may be placed in the chambers 53, the ingredients being mixed by the agitators 60, which are turned by means of the shaft 58 and the crank 59, or the pulley 30 67. The specific gravity of the calcium chloride solution may be determined accurately by means of the hydrometers 63. The advantage in having two chambers 53 is that one batch of calcium chloride solution 35 can be mixed whilst the other batch of calcium chloride solution is running out of the tank 50. The solution leaves the tank 50 by means of either of the outlets 64, depending upon which of the valves 65 is opened, and 40 the solution flows by way of the pipe 66 into the pipe 10.

When the delivery member or skip 3 is lowered, as in Figure 1 of the drawings, the arm 24, responding to the weight 25, 45 is disposed approximately at right angles to the discharge pipe 11, and the parts then are arranged as shown in Figure 3 of the drawings. The port 17 of the valve casing 16 is closed, so that liquid cannot flow through 50 the port 26 of the valve 23, the port 28 in the valve appearing in communication with the port 16 of the valve casing 15, and the port 27 in the valve 23 being in communication with the port 18 of the valve casing. 55 Calcium chloride solution, or any other substance which it is desired to add to the mixture of concrete, flows from the tank 50, in the way hereinbefore described, through the pipe 10, and flows by way of the port 16, 60 the port 28, the port 27, the port 18, and the tubes 19 and 20, into the measuring receptacle, until the measuring receptacle is filled, as shown in Figure 3 of the drawings. During the filling of the measuring receptacle 65 the air in the measuring receptacle

escapes by way of the outlet 7. Ultimately, the casing 8 fills with liquid, and the valve 19 rises and closes the outlet for the casing 18, so that the liquid cannot escape. The valve 9 is shown in the position specified, in 70 Figure 3 of the drawings.

When the skip 3 is swung up into the position of Figure 2, to discharge its contents into the drum 2, the measuring receptacle 6 attains a substantially vertical position, as shown in Figures 4 and 2 of the drawings, and the liquid in the measuring receptacle 6 is discharged through the pipe 11 into the drum 2 through the end 14 of the pipe 11, the end 14 of the pipe having 80 been so placed, by the raising of the skip 3, that the liquid will run into the drum 2, from the end 14 of the pipe 11. When the skip 3 is raised, the arm 24, carrying the weight 25, remains in a substantially vertical position, and relative movement takes place between the valve casing 15 and the valve 23. By the time that the skip 3 has been raised, and when the receptacle 6 is in the position shown in Figure 4, the port 16 90 in the valve casing 15 is closed, the port 27 in the rotatable valve 23 is closed, the port 28 in the valve registers with the port 18 in the valve casing 15, and the port 26 registers with the port 17 in the valve casing. 95 The liquid can then run out of the measuring receptacle 6 through the tubes 20 and 19, through the ports 18 and 28, and through the ports 26 and 17, into the pipe 11, from which the liquid flows into the 100 drum 2, as hereinbefore described. As the liquid runs out of the receptacle 6, whilst the receptacle is in the position shown in Figure 4, the float valve 9 is jarred or sucked to an open position, so that air can enter 105 through the member 7 and vent the receptacle 6.

It is to be observed that the coupling 21 may be detached from the tube 20, and, then, the tube 20 can be advanced or retracted, in the receptacle 6, the tube 20 being threaded into the foot plate 2. In this way, the amount of liquid that is left in the receptacle 6, when the receptacle is in a vertical position, as shown in Figure 4, may be varied, and, consequently, an adjustment may be made in the amount of liquid that is discharged from the receptacle 6 when the receptacle is shifted from the horizontal position of Figure 3 to the vertical position of 115 Figure 4.

The device is simple in construction, but it affords an efficient means whereby calcium chloride solution, in a measured quantity, 120 may be discharged into a mass of concrete aggregate, to accelerate the setting of the concrete. Although the device is intended for the handling of calcium chloride solution, it may be used, of course, for discharging any other substance into a mass of 125 concrete.

crete: for instance, it may be employed to deliver coloring matter into concrete which is to be tinted.

What is claimed is:—

- 5 1. In a device of the class described, a mixing drum, a loading skip therefor, a measuring receptacle, means providing a liquid inlet and a liquid outlet for the receptacle, means providing an opening to the atmosphere from said receptacle, means for mounting the receptacle on said skip in such position that the outlet will discharge into said drum when the skip is raised, and gravity-operated valve means responsive to the movement of the receptacle with the skip to open the inlet when the receptacle is lowered, and to close the inlet when the skip is raised.
- 10 2. In a device of the class described, a mixing drum, a loading skip therefor, a measuring receptacle, means providing a liquid inlet and a liquid outlet for the receptacle, means for mounting the receptacle on said skip in such position that the outlet will discharge into said drum when the skip is raised, a tube extended into the receptacle, means for mounting the tube adjustably, to regulate the amount that the tube extends into the receptacle, a valve cas-

ing connected to the tube, to the liquid inlet, 30 and to the liquid outlet, a valve in the casting and gravity means for operating the valve responsive to the movement of the receptacle with the skip to open the inlet when the receptacle is lowered, to close the inlet 35 when the skip is raised, to open the outlet when the skip is raised, and to close the outlet when the skip is lowered.

3. In a device of the class described, a measuring receptacle provided at one end with an air vent, a float valve controlling the air vent, a tube extended into the receptacle, means for adjusting the tube longitudinally, to regulate the amount that the tube extends into the receptacle, means providing a liquid outlet and a liquid inlet for the receptacle, gravity-operated valve mechanism connecting the tube with the inlet and with the outlet, a mixer, and means for mounting the receptacle for swinging 50 movement with respect to the mixer, thereby to operate the aforesaid valve mechanism and to cause the outlet to discharge into the mixer.

In testimony that I claim the foregoing 55 as my own, I have hereto affixed my signature.

RUSSELL C. BURKET.
